Specification of Letters Patent. Patented Oct. 10, 1916.

Application filed June 18, 1912. Serial No. 704,326.

To all whom it may concern:

Be it known that I, EDWARD E. CLEMENT, a citizen of the United States, residing at Washington, in the District of Columbia, 5 have invented certain new and useful Improvement in Telephone-Exchange Systems, of which the following is a specification, reference being had therein to the accompanying drawing.

0 My invention relates to telephone exchange systems, and particularly to semi-automatic systems in which the interconnection of subscribers for conversation is effected by means of automatic switches 15 controlled by operators located at a central office, in response to oral instructions received from the calling subscribers.

The object of the present invention is to give the calling subscribers direct access to 20 the operators, without going through any portion of the switches or trunks used for interconnections. For this purpose, I provide a certain number of auxiliary switches which I call primary selectors, whose function is to automatically connect with calling lines in response to the subscribers' acts in calling; a number of associated auxiliary switches which I call secondary selectors, whose function is to select the idle operators 25 and connect the primary selectors therewith; a number of auxiliary switches associated with the operators' positions, which I call distributing switches, whose function is to connect the operators with idle connecting trunks and switches; and finally the usual complement of automatic selector switches commonly employed in any such systems as for example the Strowger, which receive impulses from the operators through 30 the distributing switches, after the operators have communicated with the calling subscribers through the primary and secondary switches.

A characteristic feature of the system is 45 this, that the automatic connective switches are all worked by definite impulses transmitted from the operators' keys and sending machine, so that the number of the calling subscriber being first known to the operator, 50 she sends the proper impulses to step up the connective switches on one end to the calling line contacts, and on the other end to the called line contacts. Thus, the calling

and called parties are both connected simultaneously to the connective switching trunks, 55 which are brought into service at the moment of use only, and are never idle during the period between the call and the completion of the connection. In systems heretofore proposed, one portion of the connective trunks has become connected with a calling line in response to a call, and remains so connected until the operator could obtain the number and complete the connection. By the present arrangement I increase the efficiency of the connective trunks 60 and switches, and effect a more perfect distribution of calling lines among all the operators.

A number of subsidiary features of the 70 invention and advantages flowing therefrom will appear from the detail description.

My invention is illustrated in the accompanying drawings in which—

Figure 1 is a diagram of a subscriber's 75 line, a central office connector containing terminals of this and other lines, and a primary switch also containing terminals of the same lines, with its associated secondary switch containing terminals of the operator's circuits. Fig. 2 is a diagram constituting a continuation of Fig. 1, and showing a permanently connected pair of first selectors, with a pair of associated second selectors through which connection may be established between the connectors of Figs. 1 and 4. Fig. 3 is a diagram constituting a continuation of Fig. 2 and showing an operator's position, with primary and secondary distributing switches to connect the operator 80 to the central switching trunks of Fig. 2, also a portion of the wiring extending to the secondary selector switch of Fig. 1. Fig. 4 is a diagram constituting a further continuation of Fig. 2, and showing a connector and line circuit, similar to those of Fig. 1, but without the primary and secondary selectors.

In reading the drawings, Figs. 1, 2 and 4 should be placed side by side from left to 100 right, and Fig. 3 below Fig. 2. The connection which will be traced from one subscriber to another is supposed to originate at the station A on the left of Fig. 1. When subscriber A calls by taking down his receiver, his line becomes connected automatic- 105

cally through the switches S and S' of Fig. 1 to the operator's position in Fig. 3. The operator ascertains both the number of subscriber A and the number of the subscriber 5 wanted, who for purposes of description we will assume to be subscriber A' in Fig. 4. The operator sets up these two numbers on the two sets of keys at K' and K respectively, and impulses are then directed from 10 the sending machine D through the keys which have been depressed by way of the wires 67-68 and 167-168 and the switches S², S³ to the first selector switches S⁴ and S⁴⁰ respectively in Fig. 2. The impulses 15 from the keys K' to the switch S⁴ cause selection through the switches S⁵, S⁶ of the calling line; and the impulses from keys K² to the switch S⁴⁰ cause selection through the switches S⁵⁰ and S⁶⁰ of the wanted line. A 20 circuit for conversation is thus established extending from A in Fig. 1 through the switches of Figs. 1, 2 and 4 to the station A' in Fig. 4, and thereupon the operators' switches S² and S³ become automatically 25 disconnected, leaving the conversation circuit under the exclusive control of the connected subscribers. As soon as the operator has set up the numbers, and depressed her starting key K³, her work on this connection 30 is finished, and the primary and secondary switches S and S' are automatically released, ready to pick up another calling line and another operator's position. Each operator can be provided with more than one 35 of the double sets of keys shown in Fig. 3, so as to increase her capacity for answering calls. The description herein will be limited, however, for convenience, to the single equipment shown in Fig. 3.

40 The switches S⁴-S⁴⁰, S⁵-S⁵⁰, S⁶-S⁶⁰, in Figs. 2, 1 and 4 respectively, are shown of the well known Strowger type, which require no detailed description. The two switches S⁴ and S⁴⁰ in Fig. 2 are both what are known as 45 "first selectors," each adapted to select an idle trunk in a desired thousands group. These two switches are permanently connected through the condensers C and C', the switch S⁴ always being used to find the calling line, while the switch S⁴⁰ is always used to find 50 the wanted line. These are the only switches thus limited in their functions however, since the second selectors S⁵ and S⁵⁰, and the connectors S⁶ and S⁶⁰ are employed indiscriminately in the selection of both calling and wanted lines. An economy is hereby effected, because each line, instead of having multiples, such as c³-c⁴ and c²⁰³-c²⁰⁴, in two different classes of switches, now has 55 multiples in only one class, viz., the connectors S⁶ and S⁶⁰. Since these connectors are available for either calling in or calling out, a smaller number will suffice, probably not more than 15 per cent. of the number of lines 60 in general. The same is true of the second

selectors, which contain the terminals c¹¹-c¹²-c⁹⁰, c²¹¹-c²¹²-c²²⁴ of the connector switches and which may be reduced proportionately. The number of multiples c¹⁷-c¹⁸-c⁹⁶, c²¹⁷-c²¹⁸-c²⁹⁶, representing 70 the second selectors in the banks of the first selectors S⁴ and S⁴⁰ will be greater than in the ordinary systems, because the second selectors would be accessible in both directions, that is to say from both classes of first 75 selector switches. As the percentage of second selectors is reduced however, this need not unduly increase or change the trunk provision in the first selectors.

The primary and secondary switches S⁸⁰ and S' require some description. These are electrically connected in pairs, and are power driven, having rotary motion only, and always traveling in the same direction. For convenience I have shown one pair of 85 these switches mounted so as to be driven by a common shaft s, carrying a pulley s' connected to a source of power through a belt s². The switch S comprises a bank of contacts of which only those on one side 90 are shown, at c⁸⁴-c²⁵-c⁵⁵-c⁶³. Sweeping over these are the wipers w³⁴-w²⁵-w⁵⁵-w⁶³, which are carried by but insulated from a metal sleeve s⁵ surrounding the spindle s. At the upper end of this sleeve I provide 95 a sliding collar s⁸, splined or feathered to the sleeve so as to turn with it, this collar being one element of a clutch of which the other element s⁴ is fixed rigidly on the spindle s. The element s⁴ has a finger projecting 100 on one side, and the collar s⁸ has a corresponding finger projecting outwardly and upwardly from its body so that when it has slid up in the position shown in Fig. 1, the two fingers will engage, and the collar s⁸ will 105 rotate with the spindle s, so as to sweep its wipers over the bank contacts. This clutch connection is controlled by the electromagnet M and when this magnet is energized, its lever 1 forces down the clutch so as to disengage the fingers, and stop the switch S with its wipers resting upon one pair of contacts only. Suitable springs must be provided to secure this action, such as a retractile spring for the armature lever 1.

110 The secondary switch S' is similar in its structure and arrangement to the switch S, with the single exception that its clutch is engaged when its controlling magnet M' is energized, and disengaged at all other 115 times. The reason for this difference is that the switch S is constantly rotating in order to sweep its wipers over the line contacts, whereas the switch S' is normally at rest with its wipers touching the contacts 120 of an idle operator's circuit. As soon as the operator has obtained the numbers of the lines calling and wanted, and having set them up, presses her starting key K³, a circuit is closed for the relay R⁵ in Fig. 125 130

1, which becoming energized closes the circuit of the clutch magnet M' , which in turn raises the clutch member s^{13} to engage the spindle member s^{14} , to thereby rotate the sleeve s^{15} and carry the wipers w^{72} — w^{43} — w^{58} — w^{64} — w^{37} off the contacts of the operator in question. Moreover, it will be observed that the relay R^5 is self-locking, and after once becoming energized in this manner it will remain energized, so as to keep the sleeve s^{15} rotating, as long as the wiper w^{43} is passing over contacts c^{43} appertaining to operators who are busy. Each operator's key set has a "busy" relay R^4 , for this purpose, and as will hereafter appear, so long as this relay is energized by reason of the operator's key set being engaged in transmitting a call, so long will the battery be connected to the contacts c^{63} in all the secondary switches S' , through wire 43. Thus the switch S' when released, will continue its movement until an idle operator is reached and will then come to rest; and conversely as soon as the operator's key set is again free, its relay R^4 will become deenergized and any of the switches S' may again come to rest on her contacts.

The bank of each primary switch S may conveniently contain the multiple contacts of 100 lines, and the bank of each secondary switch S' may contain multiple contacts for all the operators in the exchange. Thus, there should be at least as many pairs of switches S — S' as there are groups of 100 subscribers each; and should traffic conditions render it desirable or necessary, there may be two, three or more pairs of switches S — S' for each group of subscribers. The actual number depends upon the number of simultaneous calls to be provided for in any particular group, and under ordinary traffic conditions, this would rarely exceed five and would commonly be no more than three. Each group of subscribers thus has access through each of its pairs of primary and secondary switches S — S' to all of the operators, and therefore any line in the exchange may become connected when calling to any operator. In this particular my present invention is identical with that disclosed in my prior application, serial No. 277,524, filed September 8, 1905.

The operator's key set and the sending machine D are of substantially the same construction as shown in my prior application, Serial No. 611,923, filed March 2, 1911.

The keys K' and K^2 are in rows of ten, there being four rows shown in each set which is sufficient for an exchange of 10,000 lines. In addition to these four rows a fifth row is shown on the right of the key set K^2 by which the selective ringing generator is connected for party line signaling, which however has nothing to do with the present invention. The several keys in each of these

sets are connected so as to derive their impulses from one to ten, from the several spring contacts resting on the drum D which is supposed to be constantly rotated by a suitable motor as shown. The drum carries four sets of teeth, so as to send impulses from one to ten four times in succession, and each strip of keys in the set K' or K^2 is cut on in succession, by means of suitable relays or switches so as to prevent confusion in transmission. At the end of each rotation of the machine, that is to say at the end of a complete cycle of impulses, the spring 136 is closed to ground by wire 135 which is connected to the various key sets and through each to the wire 71 and the relay R^{23} . Thus after the full number is transmitted, the relay R^{23} is automatically energized, to deenergize and release the "busy" relay R^4 , which in turn restores the ground to the relay R^6 for the purpose of energizing that relay through the wire 46, the wipers w^{46} and w^{40} , etc., and causing the switch S^2 to step off the multiple contacts of the trunk switch S^3 , so as to disconnect the operator, which of course is necessary after the connection is thus completed.

The switches S^3 call the primary distributing switches. Each has a spindle driven step by step by means of an electromagnet M^3 , which is normally energized by impulses from a commutator I whenever the relay R^{25} is active. This relay depends for its current upon a circuit from battery through the wire 141 and wiper w^{141} , which wiper is moved around by the spindle to test contacts c^{141} connected to the several trunks in Fig. 2. The contacts c^{141} , c^{69} and c^{70} are not multiplied, but each trunk has one set of these contacts in one only of the switches S^3 . Thus, in a 10,000 line exchange, assuming 1000 trunks, 50 switches S^3 with 20 contacts each, or 20 switches with 50 contacts each, would suffice to give access to all of the trunks. Each of the switches S^3 is represented by multiple contacts c^{46} — c^{67} — c^{68} in the banks of each of the operators' secondary distributing switches S^2 . Assuming 25 operators, each with two key sets, and each key set provided with a switch S^2 , there would be a total of 50 switches S^2 , each containing a multiple contact for each of the switches S^3 , so there would be 50 multiples connected to each of the wires in the set leading from switch S^3 . The switch S^3 , as hereafter appears, will always rest on the contacts of an idle trunk shown in Fig. 2, and the switch S^2 will always seek and rest upon the contacts of a switch S^3 which is thus resting on the contacts of an idle trunk. It will be observed that by the use of these primary and secondary distributing switches, any operator in the entire exchange can have access to any one of the trunks in the exchange, so that as a matter of fact, any sub-

scriber may reach any operator, and may be connected through any pair of selectors in the entire exchange, which gives the widest distribution of load, the highest efficiency in the apparatus, the lowest percentage of apparatus and wiring required, and the lowest cost of maintenance.

The detail features of my invention it is thought will sufficiently appear from the following distribution of operation. It is assumed as already stated, that subscriber A in Fig. 1 calls by taking down his receiver.

When the subscriber A takes down his receiver the line circuit 1-2 is closed and his line relay R is energized by current over the following path: battery lead 21, R, 22, r^{21} , line wire 1, through subscriber's telephone apparatus, line wire 2, r^{22} , 23, and ground. Thereupon the armatures r' , r^2 and r^3 of relay R pull up. The armature r' connects battery with the contact c^{25} of the primary selector S through the following path: battery lead 21, r' , 24, r^{22} , 25, c^{25} . The wiper w^{25} of the primary selector switch S coming into engagement with the contact c^{25} energizes the relay R', the energizing current being from battery to the wiper c^{25} as above traced and thence through wiper w^{25} , 26, R', 27, r^{21} , to ground. The relay R' attracts its armatures completing the circuit of its holding winding, from battery lead 28, r^{12} , 29, R', 30, 27, r^{21} , to ground and at the same time energizes the clutch magnet M by current from battery lead 31, M, 32, r^{11} , to ground. The magnet M attracts its armature throwing down the clutch lever 2 which disengages the lower clutch member s^3 from the upper rotating member s^4 , and brings it down onto the loose wiper sleeve s^5 , the friction between the lever 2 and clutch member s^3 checking the motion of the sleeve and causing the wipers w^{34} , w^{25} , w^{55} and w^{63} to rest on their respective contacts c^{34} , c^{25} , c^{55} and c^{63} . Simultaneously, the energizing circuit of relay R² is completed from battery lead 35, R², 34, c^{34} , w^{34} , 35', r^{13} to ground, and R² attracts its armatures locking itself through armature r^{21} , 36, r^{223} to ground, and disconnecting battery from the multiple contacts c^{25} at r^{22} so that other primary selectors whose wipers w^{25} pass over the multiples c^{25} will not be affected. Simultaneously also with the actuation of the clutch magnet M the wiper w^{37} of the secondary selector switch S' is grounded through the following connections: w^{37} , 38, r^{51} , 39, r^{14} , to ground, and assuming that the wipers of the switch S' are resting on the multiple contacts of an idle operator's trunk, the operator's line relay R³, Fig. 3 is energized by current from battery lead 36, R³, 37, (37 Fig. 2, 37 Fig. 1) contact c^{37} , wiper w^{37} to ground as above traced. The energization of relay R³ completes the circuit of the line lamp L through the armature r^{31} , and the energizing circuit

of the operator's busy relay R⁴ Fig. 3, the latter circuit being from battery lead 36, through r^{32} , 40, R⁴, to ground, whereupon the relay R⁴ attracts its armatures, locking itself through r^{41} , 40, r^{231} , onto battery lead 42, and connects battery onto the conductors 43 and 44 leading to the multiple contacts c^{43} and c^{46} on which rest the wipers of the secondary selector switch S' and primary distributing switch S² respectively. The former connection may be traced from battery lead 42 through r^{42} , 43, (43 Fig. 2, 43 Fig. 1) to c^{43} and the latter connection from battery lead 42 Fig. 3; through r^{43} , 44, r^{61} , 45, 46, w^{46} to c^{46} . The former circuit establishes a busy test which does not affect the secondary selector S' through which the call came as the circuit of the clutch relay R⁵ of said switch is open at r^{14} . However any other secondary selector switches S' that may be connected onto the multiples c^{43} immediately step around to the contacts of the next idle operator, their clutch relays R⁵ being energized by current from battery to the multiples c^{43} as above traced and thence through w^{43} , 44, R⁵, 45, r^{14} to ground. The relay R⁵ attracts its armatures, locking itself to ground and energizing the clutch magnet M' by current over the following path: battery lead 46, M', 47, r^{52} , to ground. The clutch magnet attracts its armature, throwing up the lever 2 which brings the clutch member s^{13} up into engagement with the constantly rotating member s^{14} , causing the wiper sleeve to rotate, and the test wiper w^{43} to sweep over the test contacts c^{43} until one of said contacts representing an idle operator (that is, one on which there is no battery connection) is found, whereupon the clutch relay R⁵ being deprived of current releases its armatures breaking the circuit of the clutch magnet which disengages the clutch members and brings the wipers of the switch to rest on the contacts of an idle operator's trunk.

Should a secondary selector be in the act of testing when the relay R' is energized depriving its clutch relay R⁵ of one of its ground connections at r^{14} , it would continue to test as the relay R⁵ is locked onto ground through r^{53} and falls back only when the wiper w^{43} fails to find battery. Similarly the test on contacts c^{46} of switch S² Fig. 3 does not affect the switch through which it originated as the circuit of the stepping relay R⁶ of that switch is opened at r^{44} as soon as R⁴⁴ is energized, but any other primary distributing switches whose wipers w^{46} rest on the multiples of contact c^{46} will immediately begin testing for a contact representing an idle secondary distributing switch as follows: The multiples of c^{46} being connected to battery as above described, current flows through the wiper w^{46} , 46, R⁶, 48, r^{14} , to ground. The stepping relay 130

R^6 in pulling up connects battery onto the stepping magnet M^2 , which is thereupon energized at each closure of the contact springs of the interrupter I, the circuit being from 5 battery lead 42, r^{62} , 49, M^2 , 50, 52, through the contact springs of the interrupter I and to ground. The switch continues to step around until its wiper w^{46} engages a contact leading to an idle secondary distributing 10 switch S^3 (i. e. one which is connected through 137, R^{24} , 138, r^{251} to ground) whereupon the relay R^6 being deprived of its battery supply releases its armatures breaking the circuit of the stepping magnet M^2 at r^{62} 15 which causes the switch to come to rest with its wipers on contacts leading to an idle secondary distributing switch S^3 .

The completion of the busy test as above described by the attraction of the armature 20 r^{43} of relay R^4 , putting battery on multiples c^{46} causes the control relay R^{24} of the switch S^3 to open the circuit of the stepping relay R^{25} at r^{241} which places the switch S^3 under the control of the switch S^2 , the energizing 25 circuit of relay R^{24} being from battery to the contact c^{46} as previously traced and thence over wire 137, through R^{24} , 138, r^{251} to ground.

Should a primary distributing switch be 30 in the act of testing when its busy relay R^4 is pulled up by a calling subscriber it would continue to test, the circuit of its stepping relay R^6 being locked to ground through r^{63} which circuit is broken only when the 35 wiper w^{46} engages the contact of an idle trunk which deprives the relay R^6 of its battery supply.

The operator seeing the line lamp L light 40 up presses her listening key K Fig. 3 which energizes the relay R^7 by current from battery lead 53, through the contacts of key K, 54, R^7 to ground. The relay R^7 pulling up locks itself onto battery through r^{71} , 55, k , k' and battery lead 53, and at the same time 45 connects the operator's listening wires 56-57 on to the calling subscriber's line as follows: 56, r^{72} , 58, (58 Fig. 2, 58 Fig. 1) c^{55} , w^{55} , 59, w^{55} , c^{55} , 60, r^2 , 61, 1 substation A, 50 line wire 2, 62, r^3 , 63, c^{63} , w^{63} , 64, w^{64} , c^{64} , 65, (65 Fig. 2, 65 Fig. 3) r^{73} , 57. The operator ascertains the number of the calling subscriber and the number of the subscriber wanted, sets up the two numbers on her key 55 sets K' and K² respectively and depresses the starting key K³ which opens the contacts $k-k'$, and closes the contacts $k'-k^4$, and k^2-k^3 . The opening of the contacts $k-k'$ breaks the locking circuit of the listening relay R^7 which releases its armatures disconnecting the operator's listening wires 60 56, 57. The closure of contact k^2-k^3 connects battery from battery lead 53, through contacts k^2-k^3 , and conductor 66 onto a relay in the circuit of the key sets which 65 connects the key set circuits onto the im-

pulse wires 67, 68, 167, 168 and 71. (See the above referred to application Serial No. 277,524, Sept. 8, 1905). The closure of contacts $k'-k^4$ energizes the release relay R^8 Fig. 1 the circuit being from battery lead 70 53, through the contacts $k'-k^4$, 71, (72 Fig. 2, 72 Fig. 3) c^{72} , w^{72} , 73, R^8 to ground. The relay R^8 pulling up its armature r^{81} breaks the energizing circuit of the clutch relay R' which in releasing its armatures breaks the 75 circuit of the clutch magnet M. The de-energization of the clutch magnet allows the lever 2 to be pulled up by its retraction spring, bringing the clutch member s^3 into engagement with the rotating member s^4 80 which starts the primary selector switch S rotating to select the next calling subscriber. The retraction of the armature r^{14} completes the energizing circuit of the clutch relay R^5 causing the secondary selector 85 switch S' to step around in search of an idle operator's trunk the operator and circuits being as previously described. This opens the energizing circuit of the operator's line relay R^3 at c^{37} which relay releases its arma- 90 ture r^{31} , r^{32} opening the circuits of the line lamp L and busy relay R^4 at r^{31} and r^{32} respectively. The relay R^4 however remains energized through its locking circuit as previously described. The actuating impulses 95 corresponding to the number of the calling subscriber and the number of the wanted subscriber now pass from the sending machine D through the operator's key set circuit, conductors 67 and 68, 167 and 168 distributing switches S^2 S^3 , and into the circuits of the selectors and connectors shown in Figs. 1, 2 and 4 where they effect the desired connection.

The two sets of impulses corresponding to 105 the numbers of the calling and called subscribers are sent simultaneously over the conductors 67-68 and 167 and 168 respectively, the former actuating the switches S^4 , S^5 and S^6 Figs. 2 and 1 and the latter actuating the switches S^{40} , S^{50} and S^{60} Figs. 2 and 4.

As the circuits and operation of the two sets of switches are identical it is necessary to describe the operation of one set only, 115 e. g. the set which effects the connection of the calling subscriber.

Electrical impulses corresponding in number to the first digit of the calling subscriber are sent from battery over the wire 120 68 Fig. 3 energizing the vertical relay R^9 Fig. 2, the circuit being from battery through the impulse sending device Fig. 3, conductor 68, w^{68} , c^{68} , 69, w^{69} , c^{69} , 74, (74 Fig. 2) 19, x^2 , 75, R^9 , 76 to ground. At each 125 impulse the relay R^9 pulls up closing the contacts 83 and 84, and completing the energizing circuit of the vertical magnet V^x as follows: from battery lead 78, V^x , 79, 80, 81, 82, 83, 84, 85 to ground. The actuation 130

of the vertical magnet V^x causes the shaft s^x of the switch S^x together with its wipers to step up to the row of contacts whose ordinal corresponds to the first digit of the calling subscriber, and which are connected to a group of ten trunks leading to second selector switches. One impulse is now sent over the wire 67 Fig. 3 energizing the rotary relay R^{10} , current flowing from battery through the impulse sending device Fig. 3, conductor 67, w^{67} , c^{67} , 70, w^{70} , c^{70} , 86, (86 Fig. 2) 20, x^8 , 87, R^{10} to ground. The pulling up of the relay R^{10} closes the contacts 88, 84, thereby completing the energizing circuit of the relay R^{11} , the energizing current being from battery lead 89, through R^{11} , 88, 84, 85 to ground. The actuation of the relay R^{11} momentarily opens the contacts 80, 81 and closes the contacts 81, 91. The changing of these contacts 80, 81 and 91 produces no result at present and their use will be explained later. When the relay R^{11} retracts, the arms x' , x^2 , x^3 and x^4 of the side switch are moved to the second contact. The moment the switch arm x' reaches its second contact, current is supplied to the rotary vibrating magnet R^x , the actuating current being from battery lead 92, through R^x , 93, x' to ground. This magnet continues to vibrate and each time it pulls up it rotates the wipers of the switch one step. The test wiper w^{90} of the switch passes over the contacts c^{90} successively until it finds an idle trunk. As the wiper w^{90} passes over the contacts leading to busy trunks the relay R^{11} will be energized by current from battery lead 89 through R^{11} , 94, x^4 , 95, release relay R^{12} , 96, w^{90} , c^{90} and to ground through the corresponding first selector switch of each busy trunk by way of the multiple terminals c^{90} , back through the release relay corresponding to R^{12} and to ground, the switch arm corresponding to x^4 of the busy selector switch being of course upon its third contact. It will be observed that this circuit includes the relay R^{11} and the test relay R^{12} and the corresponding test relay in the busy switch, in series. The relay R^{11} being high wound will operate on this circuit while the other two relays will not. When an idle trunk is found this test circuit is broken since the wiper w^{90} of the first selector switch is no longer grounded. The energizing circuit therefore of the relay R^{11} is broken and when it retracts, the arms x' , x^2 , x^3 and x^4 of the side switch are moved to their third contacts. The movement of the arm x' breaks the actuating circuit of the rotary magnet R^x , stopping the wipers w^{17} and w^{18} on the contacts c^{17} and c^{18} of an idle trunk leading to a second selector. Battery impulses corresponding to the second digit of the calling subscriber are now sent along the wire 74 over the path previously traced, to the trunk conductor 19 and through the connected trunk conductor 15. At each impulse the relay R^{18} pulls up, actuating current being from battery, to trunk 15 over the path already traced, thence through y^2 , 97, R^{13} , 98 to ground. The pulling up of the relay R^{18} closes the contacts 99, and 100. This energizes the vertical magnet V^y , the energizing current being from battery lead 102 through V^y , 103, 104, 105, 106, 99, 100 to ground. The actuation of the vertical relay V^y causes the shaft S^y of the switch S^y to step up to the row of contacts whose ordinal corresponds to the second digit of the calling subscriber and which are connected to a group of ten trunks leading to connector switches. One impulse is again sent over the trunk conductor 20 as previously described and thence through the switch arm x^8 , 18, w^{18} , c^{18} , 16, y^8 , 107, R^{14} and to ground energizing the relay R^{14} which pulls up and closes the contacts 108 and 100 thus actuating the relay R^{15} , the energizing circuit of the latter being from battery lead 101 through R^{15} , 108, 100 to ground. The retraction of the relay R^{15} as in the case of the first selector switch S^4 , causes a movement of the arms y' , y^2 , y^3 and y^4 to their second positions. This energizes the rotary magnet R^y in precisely the same manner as its corresponding magnet R^x is energized, and the shaft s^y is now stepped around to pick out an idle trunk leading to the connector switch S^y . The test wiper w^{90} passes over the contacts c^{90} and the relay R^{16} is energized in a manner and over circuits similar to relay R^{11} , until the idle trunk is found, at which time it lets go and moves the side switch arms y' , y^2 , y^3 and y^4 to their third position. The calling subscriber is now connected to a connector switch containing the contacts onto which his line is multiplied. Impulses corresponding to the third digit of the calling subscriber are now sent over the trunk conductors 19, 15 and 11. The relay R^{16} is operated closing the contacts 110 and 111, and energizing the vertical magnet V^z , the energizing circuit of the latter being from battery lead 112 through V^z , 113, z' , 114, 115, 116, 117, 110, 111 to ground. Thereupon the spindle s^z is stepped up to the row containing the contacts of the calling subscriber's line. One impulse is now sent over the connected trunks 20, 16 and 12. This energizes the relay R^{17} which pulls up closing the contacts 118, 111 and energizes the relay R^{18} in the same manner as relays R^{11} and R^{14} as heretofore described. On the retraction of the latter relay the arms z' , z^2 , z^3 and z^4 are moved to their second contacts the arm z' cutting off the vertical magnet V^z and connecting the rotary magnet R^z . Impulses corresponding to the fourth or last digit of the calling subscriber

are now sent over the connected trunks 19, 15 and 11. These impulses actuate the rotary magnet R^z , which steps the switch shaft s^z around bringing its wipers w^3 , w^4 into engagement with the contacts c^3 , c^4 leading to the calling subscriber's line. A final single impulse is now sent over the connected trunks 20, 16 and 12. The relay R^{17} is actuated and again closes the actuating circuit of the relay R^{18} . It will be remembered that the switch arms z' , z^2 , z^3 and z^4 are now in their second position. The actuation of the relay R^{18} closes the springs 119 and 120, and should a third subscriber have been connected to the multiples c^3-c^4 of subscriber A before the connection therewith of the wipers w^3-w^4 as above described, a busy test circuit would be established as follows: battery lead 121, release relay R^{19} , 122, 123, 20 124, 120, 119, 125, z^4 , 126, w^3 , contact c^3 and its multiples and back upon the tip side of the connector trunk of the previously connected subscriber and to ground through the tip relay of that trunk corresponding 25 to R^{20} . The energizing circuit of the release relay R^{19} being thus completed this relay is actuated and the pulling up of its armature r^{191} grounds the release magnet M^4 which restores the connector switch S^6 to its original position.

Assuming however that the contingency just described has not occurred and the tip multiples c^3 of the calling subscriber are entirely free, the test circuit above described will not be completed, and the momentary closure of the springs 119 and 120 will therefore not affect the switch. The retraction of the armature of relay R^{18} moves the side switch arms z' , z^2 , z^3 and z^4 into their third position. The sleeve relay R^{21} is energized in series with the cut-off relay R^{22} of the calling subscriber's line, the circuit being from battery lead 128 through R^{21} , 129, 10, 130, 131, 8, z^3 ; 6, w^4 , c^4 , 4, R^{22} to ground. The pulling up of the cut-off relay R^{22} opens the locking circuit of the relay R^2 at r^{223} , and connects the calling subscriber's line to the extensions leading to the contacts c^3 and c^4 , and completes the actuating circuit of the tip relay R^{20} the circuit being from battery to the conductor 4 in the manner already traced, thence through armature r^{222} , line wire 2, sub-station A, back over the line wire 1, r^{221} , 3, c^3 , w^3 , 5, z^2 , 7, 132, 133, 9, 134, R^{20} to ground. It will be seen that the circuit of the ringing relay R^{31} is completed on the pulling up of the sleeve relay R^{21} so far as to put the former under the control of the interrupter I. However, the interrupter is so permanently connected with the impulse sending device that the period included between the cessation of the last test impulse and the pulling up of the tip relay as above described, passes during the interval in which

the circuit through I is broken. This protects the calling subscriber from being rung while his receiver is off the hook.

The actuation of the relay R^{20} causes it to attract its armature r^{201} which closes the energizing circuit of the relay R^{30} said circuit being from battery lead 128 through r^{211} , 146, 147, r^{201} , 148, R^{30} , 149, 150, 151 to ground. It will be noted that the contacts 75 150 and 151 are closed immediately on the first vertical motion of the shaft s^z of the connector switch S^6 . The energization of the relay R^{30} breaks the actuating circuit of the ringing relay R^{31} by the attraction of the armature r^{301} . After the relay R^{30} 80 has pulled up it is locked, the locking circuit being from battery lead 128 through armature r^{302} , 152, R^{30} and to ground as above traced. This establishes the clearing out circuit hereinafter described.

After the last impulse is sent over the connected trunks the distributing switches S^2 and S^3 Fig. 3 are restored to their normal or idle condition as follows: At the end of the cycle of impulses the relay R^{23} is momentarily energized by the closure of a pair of springs 136 on the impulse sending machine shown at D in Fig. 3, the circuit being from battery lead 42, through R^{23} , 71 through the operator's key set, wire 135, 95 springs 136, to ground. The energization of relay R^{23} causes it to attract its armature r^{231} which opens the locking circuit of the busy relay R^4 . Thereupon the armatures of relay R^4 fall back. The armature r^{42} disconnects battery from the busy test wire 43 leading to the secondary selector switches. The falling back of armature r^{43} takes the battery test off the wiper C^{46} and the armature r^{44} connects one terminal of the stepping relay R^6 to ground. The removal of battery from the wiper C^{46} deprives the control relay R^{24} of its energizing current which releases its armature r^{241} and connects one terminal of the stepping relay R^{25} to battery, and as the side switch arm w' Fig. 2 is now in its third position the relay R^{25} is energized by current from battery lead 139, through r^{241} , 140, R^{25} , 141, w^{141} , c^{141} , 142 (142 Fig. 2) w' to ground. The relay R^{25} now attracts its armature r^{252} which causes the stepping magnet M^3 to be energized and step the switch S^3 around one step at each closure of the contact spring of the interrupter I, the circuit being from battery lead 143, through r^{252} , 144, M^3 , 145, 52, interrupter I to ground. The switch S^3 continues to step around until its wipers engage contacts leading to an idle pair of first selectors *i.e.* a pair of selectors 120 whose side switches are not in the third position, whereupon the relay R^{25} being deprived of its ground connection, is deenergized and releases its armature r^{252} which opens the circuit of the magnet M^3 bringing 125 130

ing the wipers of the switch S^3 to rest on the contacts leading to the idle set of twin first selectors. Any other off normal means associated with the first selectors S^4 and S^{40} 5 may be used instead of the side switch.

While the switch S^3 is testing for an idle trunk the armature r^{258} keeps battery connected onto the wire 137 leading to the multiple contacts C^{46} thus establishing a busy 10 test which protects the switch S^3 against any interruption while in the act of testing. This temporary busy test, however, does not affect the relay R^{24} as its circuit is open at r^{251} . Meanwhile the secondary distributing 15 switch S^2 tests for an idle primary switch and finds one in the manner previously described, the circuit of stepping magnet M^2 having been completed by relay R^6 when R^4 was first deenergized.

20 The calling subscriber A is now connected through to the twin first selectors S^4 and S^{40} and from S^{40} through S^{50} and S^{60} onto the terminals of the called subscriber A'. The connection from S^{40} onto the terminals of station A' is made simultaneously with the operation of connections above described, so that at the cessation of the last test impulse the side switches Z and Z' are simultaneously moved into their third positions. If desired 30 however, the two sets of actuating impulses may be made asynchronous in time with attendant advantages. Any convenient means may be used for this purpose, such for instance as two sending machines operating 35 in asynchronism, and associated with each of k^1 and k^2 .

As the busy test for A' is the same as that described for A we will assume that A' is not busy and that the receiver is on 40 the hook at that station. When the arm Z^{13} is moved onto its third position the relays R^{26} and R^{27} Fig. 4 are energized by current from battery lead 153 through R^{26} , 154, 210, 162, 163, 208, Z^{13} , 206, w^{204} , c^{204} , 204, R^{27} to 45 ground. The relay R^{27} attracts its armatures r^{271} , r^{272} , r^{273} and connects the line wires 201—202 onto the extensions 203—204.

The energization of the sleeve relay R^{28} completes the circuit of the ringing relay 50 R^{28} which is energized for a predetermined time at each revolution of the interrupter I, the circuit being from battery lead 153 through armature r^{281} , 176, 157, r^{282} , 158, R^{28} , 159 and to ground through the interrupter I. At each energization of the relay R^{28} it attracts its armature disconnecting the switch circuit at the spring contacts 160—161 and 162—163 and connecting the generator G onto the tip and sleeve sides 60 of the subscriber's line at 164—161 and 163—165. The ringing of the subscriber's bell takes place therefore by current over one side of the line and back over the other. When the subscriber answers the tip relay 65 R^{29} is actuated the circuit being from bat-

tery to the extension 204 in the manner already traced thence over the sleeve side of the line by way of armature r^{272} through the substation apparatus A' back upon the tip side and through r^{271} , 203, c^{20} , w^{203} , 205, z^{12} , 207, 161, 160, 209, 166, R^{29} to ground. This happens, of course, at an interval when the interrupter I has cut off current from the ringing relay R^{28} , allowing it to fall back and close the contacts 160—161, and 75 162—163. The attraction of the armature r^{281} closes the energizing circuit of the relay R^{32} said circuit being from battery lead 153 through r^{261} , 173, 174, r^{281} , 166, R^{32} , 169, off normal contacts 170, 171 to ground. The 80 energization of the relay R^{32} causes the breaking of the actuating circuit of the ringing relay R^{28} by the attraction of the armature r^{321} . After the relay R^{32} has pulled up it is locked, the locking circuit being from battery lead 153 through armature r^{322} , 172, R^{32} , and to ground as above traced. The pulling up of the relay R^{32} establishes a clearing out circuit which is identical with that established in the connector circuit of subscriber A.

The subscribers A and A' are now connected for conversation, the talking circuit being as indicated in heavy lines. The battery supply circuit for A and A' is the same 95 as that traced for the energization of the tip relays R^{20} and R^{20} , respectively.

When the conversation is ended the clearing out is accomplished by either subscriber hanging up his receiver. Assuming that subscriber A first hangs up his receiver, the energizing circuit of the tip relay R^{20} is opened at his hook H and said relay releasing its armatures r^{201} and r^{202} completes the energizing circuit of the release relays R^{19} Fig. 1, and R^{37} Fig. 2 as follows: battery lead 121, Fig. 1, R^{19} , 122, 123, 174, r^{303} , 175, r^{202} , 176, 177, c^{90} , w^{90} , Fig. 2, 90, R^{37} , y^4 to ground. The pulling up of the release relay R^{19} completes the energizing circuit of the release magnet M^4 , 179, r^{101} to ground. The actuation of the magnet M^4 restores the connector switch s^6 to its normal position. The actuation of the relay R^{37} closes the springs 182, 183, which completes the energizing circuit 115 of the release magnet M^6 , and relay R^{12} as follows: battery lead 180, M^6 , 181, 182, 183, 184, c^{90} , w^{90} , 96, R^{12} , 95, x^4 to ground. The actuation of the release magnet M^6 restores the switch S^8 while the actuation of the relay R^{12} closes the spring contacts 186 and 187, and thereby completing the energizing 120 circuits of the release magnet M^6 , and the release relay R^{38} , the former circuit being from battery lead 180 through M^6 , 185, 186, 187 to ground and the latter from battery lead 188 through R^{38} , 189, 190, 186, 187 to ground. The actuation of the release magnet M^6 restores the switch S^4 to its normal 125 position.

The actuation of relay R^{38} closes the contact springs 191, 192 and 193 which connects battery to both sides of the trunk from the condensers C , C' of the first selector S^{40} on 5 through to the condensers C^2 , C^3 of the connector switch S^{60} . This causes the relays R^{39} and R^{40} to pull up simultaneously, the energizing circuit of the former being from battery lead 89 through 193, 192, 194 over 10 the tip side of the connected trunk through R^{39} , 196 to ground and that of the latter from battery lead 89 through 193, 191, 196, 15 over the sleeve side of the trunk through the relay K^0 to ground. The relays R^{39} and R^{40} pull up closing the contact springs 221 20 and 222 which closure energizes the relays K^{11} and R^{42} in series, the circuit being from battery lead 198 Fig. 4, through R^{41} , 149, 200, 221, 222, 223, 224, s^{224} , w^{224} Fig. 2, 25 225, R^{42} , 226, x^{40} to ground. Thus, the pulling up of the relays R^{41} and R^{42} causes the releases of the switches S^{60} , S^{50} and S^{40} in the same manner as that just described for the release of the switches s^6 , s^5 and s^4 .

25 While I have shown and described the best embodiment of my invention now known to me, it is obvious that my invention may be given many embodiments without departing in any wise from its generic spirit. Moreover it is evident that there is a distinct method practised in the use of this apparatus. I therefore intend to cover in the annexed claims the subject matter of the telephone system of my invention as broadly as is my legal privilege.

Having thus described my invention what I claim and desire to secure by Letters Patent is:

1. In a telephone exchange system a plurality of subscribers' lines, a plurality of primary intercommunicating links between subscribers' lines converging upon a central point, and normally disconnected from the subscribers' lines and from each other, automatically operating connecting means and control devices at the central point for effecting connections of said links to each other and over said links in opposite directions from the central point to subscribers' lines.

2. In a telephone exchange system, a plurality of subscribers' lines, a plurality of primary intercommunicating links between subscribers' lines converging upon a central point, and normally disconnected from the subscribers' lines and from each other, connecting means and control devices at the central point for effecting connections of said links to each other and over said links in opposite directions from the central point to subscribers' lines, and means auxiliary to said primary links whereby a calling subscriber may transmit a call for a connection to the said central point.

3. In a telephone exchange system a plu-

rality of subscribers' lines a plurality of primary intercommunicating links between subscribers' lines converging upon a central point, and normally disconnected from the subscribers' lines and from each other, connecting and controlling means at the central point for effecting connections of said links to each other and over said links in opposite directions from the central point to subscribers' lines, and secondary links between the subscribers' lines and the central point over which a calling subscriber may communicate a call for a desired connection between his own line and another over said primary links.

4. In a telephone exchange system, a plurality of subscribers' lines, a plurality of primary connector links having automatic connector switches at their line ends and containing bank contacts of multiplied line terminals of said lines, cross over trunks at their inner ends for automatically interconnecting the same, an operator's key set at a central station associated with said trunks and adapted to initiate and effect connections in opposite directions by way of said connector links to calling and called lines respectively, and secondary automatic connecting links between the subscribers' lines and the operator's key set whereby the subscribers may communicate calls for desired connections to said central station.

5. In a telephone exchange system, a plurality of subscribers' lines, a plurality of primary connector links having automatic connector switches at their line ends and containing multiplied bank terminals of said lines, means at their inner ends for automatically interconnecting the same, an operator's key set at a central station associated with said means and adapted to initiate and effect connections in opposite directions over said interconnecting means by way of said connector links to calling and called lines respectively, and auxiliary links independent of the aforementioned connection extending from the subscribers' lines to the central station whereby the subscriber may initiate a call to the central station for the aforementioned connection.

6. In a telephone exchange system a plurality of subscribers' lines to be interconnected, a plurality of connector links converging upon a central point for interconnecting them, but normally disconnected therefrom and from each other, a plurality of cross over trunks for interconnecting the links, said trunks each having a first selector switch at each end containing multiples of the inner terminals of said connector links, and said connector links terminating in connector switches containing bank terminals of the subscribers' lines, impulse transmitting means associated with said trunks and adapted to transmit separate sets of selec-

tive impulses over said cross over trunks from a central point in opposite directions simultaneously to select and connect two subscribers' lines for talking through said 6 cross over trunks.

7. In a telephone exchange system, a plurality of subscribers' lines to be interconnected, a plurality of connector links converging upon a central point for interconnecting them, but normally disconnected therefrom and from each other, a plurality of cross over trunks for interconnecting the links, said trunks each having a first selector switch at each end and containing multiples of inner terminals of said connector links, and said connector links terminating in connector switches containing bank terminals of the subscribers' lines, impulse transmitting means separately connected to 10 opposite ends of said cross over trunks for the transmission of separate sets of actuating impulses to the trunk, whereby the sets of impulses are transmitted one from one end to the trunk and one from the other to 15 separately effect connection of the trunks through the connector links to calling and called lines respectively.

8. In a telephone exchange system, a plurality of subscribers' lines to be interconnected, a plurality of symmetrically arranged connecting trunks having selector switches permanently connected at each end, and an impulse sending device connected with said trunks for transmitting impulses 30 to cause said switches to effect directly controlled connections over opposite ends of the same to calling and called lines respectively.

9. In a telephone exchange system, a plurality of subscribers' lines to be interconnected, a plurality of symmetrically arranged connecting trunks having selector switches permanently connected at each end containing bank terminal connecting contacts, and an impulse sending device connected 40 with said trunks for transmitting impulses to effect connections over opposite ends of the same to calling and called lines, respectively, and means in the trunk separating the sets of impulses from each other.

10. In a telephone exchange system, a plurality of subscribers' lines, and a plurality of connector link circuits for interconnecting the same, the said circuits terminating in automatic connector switches containing multiple terminals of the lines, actuating and release magnets for said connector switches, a battery supply relay energized when the subscriber's receiver is removed from its hook, means partially closing a 50 circuit for the release magnet upon the energization of said supply relay, and means completing said release magnet circuit upon deenergization of said supply relay.

11. In a telephone exchange system, a plurality of subscribers' lines, and a plurality

of connector link circuits for interconnecting the same, the said circuits terminating in automatic connector switches containing multiple terminals of the lines, actuating and release magnets for said connector switches, means acting upon removal of the line receiver from the hook to partially close the release circuit and means acting upon the replacement of the receiver on the hook to complete the closure of said release circuit.

12. In a telephone exchange system, a plurality of subscribers' lines, and a pair of associated link circuits for interconnecting the same, each link terminating in a connector switch containing multiple terminals of the several lines, actuating and release magnets for each switch, a test circuit adapted to be closed when the wanted line is found busy to energize said release magnet, a battery supply relay through which the testing circuit is closed, and means whereby, when the wanted line is found busy, the release magnet of the testing switch will send a back release impulse over the release circuit of the associated connector link.

13. In a telephone exchange system, a plurality of subscribers' lines, a plurality of connector link circuits for interconnecting them converging upon a central point, said link circuits being normally disconnected from said lines and from each other, automatic connector switches in said links for effecting connection with said lines, actuating and releasing means for the same, means for interconnecting the inner ends of the links, a release circuit established simultaneously with any connection from the central point to a subscriber's line, actuating and release magnets for the switches of the links, a test circuit for each connector, and means associated with said circuit whereby when the wanted lines test busy, the back release impulse is sent over said release circuit energizing in order the release magnets of the links, and additional means associated with said release circuit whereby the aforesaid back release impulse is transmitted forward from the central point to the connector link at the other extreme of the connection.

14. In a telephone exchange system, a plurality of lines, automatic switches and circuits for interconnecting them, actuating and release magnets for the switches, and a release circuit and transfer connections for the same whereby a release originated at one end of a connection is transmitted backward to an intermediate point, and then forward to the opposite end of the connection and thence back to the central point.

15. In a telephone exchange system, a plurality of lines, a symmetrically arranged link for interconnecting the same provided

with selector switches at each end through which connection may be effected with calling and called lines, means conductively separating but inductively uniting the 5 opposite ends of said link, actuating and release magnets for said switches, means for originating and transmitting actuating and release impulses to the said magnets and a transfer connection for release impulses 10 from one end of said link to the other.

16. In a telephone exchange system, a plurality of lines, link circuits and automatic switches for interconnecting the same, actuating and release magnets for the 15 switches, a special release conductor associated with certain of said links and adapted to effect operation of said release magnets from one end of an established connection to an intermediate point, and a transfer connection 20 at said intermediate point whereby a release impulse is transferred from said special release conductor to and transmitted forward over the link conductors themselves to effect the release of the opposite end 25 of the connection.

17. In a telephone exchange system, a plurality of lines, a plurality of connector link circuits having automatic switches for effecting connection with the same, actuating 30 and release magnets for said switches, a second link having an automatic switch adapted to connect with any one of a plurality of said connector links; means whereby a forward release impulse may be sent over 35 said circuit to energize said release magnet, means in said connector link responsive to said release impulse to momentarily energize said release magnet over a release circuit extending through the said second link and 40 including a release magnet of said second link, and means operative upon energization of the connector release magnet to lock said release magnet through said release circuit.

18. In a telephone exchange system, a 45 plurality of subscribers' lines, and a plurality of connector link circuits having automatic switches for connecting them, actuating magnets for said automatic switches, a testing means, a ringing relay, a sending 50 machine for transmitting actuating and testing impulses to the actuating and testing magnets respectively, a circuit for said ringing relay, and means for closing the same bearing a determinate time relation to the 55 operation of said sending machine in transmitting test impulses onto the links.

19. In a telephone exchange system, a 60 plurality of subscribers' lines, and a plurality of connector link circuits having automatic switches for connecting them, actuating magnets for said automatic switches, a testing means, a ringing relay, a step control device for the switches for directly governing the stepping of the switch to desired 65 positions, means to send a testing impulse at

the close of the stepping of the switch, a circuit for said ringing relay, and means separate from the aforesaid means for testing, for closing the ringing circuit and bearing a determinate time relation to the sending 70 of said testing impulse.

20. In a telephone exchange system, a plurality of subscribers' lines, a plurality of connector links having automatic switches for connecting the same, actuating means for the switches, and testing means for the lines and a ringing relay associated with each of said connector links, a sending machine associated with the links and adapted to transmit actuating and testing impulses 75 thereover to the actuating and testing means respectively, and a circuit for the ringing relay opened and closed by a commutator having a determinate time relation as respects the sending of the test impulses, said 80 relation being such that the circuit of the ringing relay of any connector link is not closed until after the final test impulse has 85 been sent.

21. In a telephone exchange system, a plurality of subscribers' lines to be interconnected, and a plurality of double ended connector links having automatic selector switches through which connection may be effected between calling and called lines, 90 means associated with said links for simultaneously transmitting selected impulses of different order for each of said switches whereby two subscribers may be connected 95 through the links.

22. In a telephone exchange system a unitary connective link having an automatic switch at each end through which directly controlled selection of calling and called lines may respectively be made, and means conductively separating but inductively uniting said switches.

23. In a telephone exchange system a unitary connective link having an automatic switch at each end through which directly controlled selection of calling and called lines may respectively be made.

24. In an automatic telephone exchange system, a plurality of subscribers' lines to be interconnected, a plurality of connective links each containing automatic switches for effecting line connections therethrough, a plurality of operators' positions having sending machines adapted to transmit selective impulses over said links when connected thereto, a primary distributing switch and circuits containing terminals of the links, and active to select and hold in readiness an idle connective link, and a secondary distributing switch associated with each operator's position and adapted to pick out and hold in readiness a primary distributing switch which has selected and is holding in readiness an idle link.

25. In a telephone exchange system, a plu- 130

rality of subscribers' lines, a plurality of double headed connective links, symmetrically arranged automatic switches at each end, said lines being accessible for calls through the said connective links only, a plurality of operators' positions having sending machines adapted to transmit selective impulses to said links to select calling and called subscribers' lines respectively, primary distributing switches containing non-multiplied terminals of certain of the links, and adapted to select and hold in readiness each an idle link and a secondary distributing switch associated with each operator's key set and containing multiplied extension terminals of the primary distributing switches, and each adapted to select and hold in readiness a primary distributing switch whose terminals have connected with an idle link.

20 26. In a telephone exchange system, a plurality of lines, a plurality of link circuits containing automatic switches adapted to interconnect the same, an operator's key set having associated therewith means for transmitting selective impulses over said links, a distributing switch adapted to select and hold in readiness an idle link, and through which the selective impulses are transmitted from the key set to the selected link, a path auxiliary to the aforesaid links over which a subscriber may communicate a call for a given connection, and a busy relay associated with said distributing switch and active upon the transmission of a call over said auxiliary path to render the said selected idle link busy.

27. In a telephone exchange system, a plurality of lines to be interconnected, a plurality of link circuits containing automatic switches adapted to interconnect the same and including first selector trunks, an operator's key set having associated therewith means for transmitting selective impulses over said links, a distributing switch adapted to select and hold in readiness an idle first selector trunk and through which the selective impulses are transmitted from the key set to the selected link, a path auxiliary to the aforesaid links over which a subscriber may communicate a call for a given connection, a busy relay associated with said distributing switch and active upon the transmission of a call over said auxiliary path to render the said selected idle link busy, means disconnecting said auxiliary path upon the commencement of the transmission impulses, and means whereby said busy relay locks itself until the transmission of said impulses is completed.

28. In a telephone exchange system, a plurality of subscribers' lines, a plurality of double headed primary connective links having symmetrically arranged automatic switches through which the lines are accessible, a plurality of operators' key sets having

impulse transmitting means adapted simultaneously to actuate the automatic switches at each end of the trunks, a distributing switch adapted to pick out and hold an idle trunk, an auxiliary automatic connective circuit adapted to connect the subscribers with the operators' key sets independently of the aforesaid primary links and adapted to pick out and hold in readiness an idle key set for any incoming call, means whereby the operator's set and the selected idle trunk are rendered busy upon the initiation of a call over said auxiliary path, means releasing the auxiliary path for the communication of other calls upon the transmission of impulses to the selective trunk, and means whereby the operator's set and the associated distributing switch are released and again rendered idle upon the complete transmission of the actuating impulses. 65 70 75 80

29. In a telephone exchange system, a plurality of subscribers' lines, a plurality of double headed primary connective trunks having symmetrically arranged automatic switches through which the lines are accessible, a plurality of operators' key sets having impulse transmitting means adapted simultaneously to actuate the automatic switches at each end of the trunks, a distributing switch adapted to pick out and hold an idle trunk, an auxiliary automatic connective circuit adapted to connect the subscribers with the operators' key sets independently of the aforesaid primary links and adapted to pick out and hold in readiness an idle key set for any incoming call, means whereby the operator's set and the selected idle trunk are rendered busy upon the initiation of a call over said auxiliary path, means releasing the auxiliary path for the communication of other calls upon the transmission of impulses to the selective trunk. 105

30. In a telephone exchange system, a plurality of subscribers' lines, a plurality of double headed primary connective trunks having symmetrically arranged automatic switches through which the lines are accessible, a plurality of operators' key sets having impulse transmitting means adapted simultaneously to actuate the automatic switches at each end of the trunks, a distributing switch adapted to pick out and hold an idle trunk, an auxiliary automatic connective circuit adapted to connect the subscribers with the operators' key sets independently of the aforesaid primary links and adapted to pick out and hold in readiness an idle key set for any incoming call, means whereby the operator's set and the selected idle trunk are simultaneously rendered busy upon the initiation of a call over said auxiliary path, and means whereby the operator's set and the associated distributing switch are released and again rendered 110 115 120 125

idle upon the complete transmission of the actuating impulses.

31. In a telephone exchange system, a plurality of subscribers' lines to be interconnected, a plurality of double ended connective trunks having symmetrically arranged automatic selector switches at each end through which connection may be made simultaneously with two different lines, and a double key board operator's set associated therewith and adapted simultaneously to send a set of actuating impulses to each end of said trunk whereby connection may be made between the two lines through said trunk, and means in the trunk for confining the respective sets of impulses each to its own end of the trunk.

32. In a telephone exchange system, a plurality of subscribers' lines, a plurality of connector trunks adapted to interconnect the same and provided with automatic switches therefor, a plurality of operators' key sets adapted to be associated each with any one of said connector trunks, primary distributing switches each adapted automatically to select and hold in readiness an idle connector trunk, a secondary distributing switch associated with each operator's set and adapted to select and hold in readiness a primary distributing switch which holds in readiness an idle trunk, means operative upon the completion of any set of actuating impulses sent through the primary distributing switch to start the same in search of another idle trunk, and means rendering the terminals of said primary distributing switch busy during its testing operation whereby said secondary distributing switch is caused to pass from its terminals and select another idle primary distributing switch.

33. In a telephone exchange system, a plurality of lines, connective links and automatic switches for interconnecting the same, a primary distributing switch containing terminals for selection of and connection with an idle link, independently of line connection with said link, said switch after testing for and selecting an idle link, adapted to hold the same in readiness for an incoming call over a line, and means whereby said distributing switch is rendered busy and will not respond to incoming calls during its operation of testing for an idle link.

34. In a telephone exchange system, a plurality of lines to be interconnected, a plurality of connector trunks having each an automatic switch at each end adapted to interconnect the same, a plurality of operators' key sets adapted to transmit actuating impulses to said trunk to operate said switches to interconnect the said lines, a primary distributing switch through

which said operator's set may be connected with trunk, an off-normal means associated with one of the switches in each trunk, an actuating magnet for said distributing switch, and a control circuit for the same adapted to be closed by said off-normal means upon the completion of the switch actuation by impulses sent through said distributing switch, whereby said distributing switch is thereafter caused to step forward to select another idle trunk.

35. In a telephone exchange system, a plurality of subscribers' lines, and a plurality of connector trunks adapted to interconnect the same, a plurality of operators' key sets adapted each to transmit selective impulses over said trunks when connected thereto, a primary distributing switch adapted to select and hold in readiness an idle trunk, a secondary distributing switch adapted to select and hold in readiness a primary distributing switch which has selected an idle trunk, means controlled from the connected trunks to start the primary distributing switches to select idle trunks upon the complete transmission of any set of impulses, and a starting circuit for the secondary distributing switch controlled jointly by the transmitting device of the operator's set and the starting device of the primary distributing switch.

36. In a telephone exchange system, a plurality of subscribers' lines, a plurality of automatic connective links for interconnecting them, an operator's key set for transmitting selective impulses over the links, a distributing switch between the key set and the links through which the impulses are sent to the links, said switch being adapted to pick out and connect to said operator's set an idle link, an actuating magnet for said switch and a control circuit for said magnet controlled jointly by off-normal means in said links and said operator's key set.

37. In a telephone exchange system, a plurality of lines, a plurality of links containing automatic switches for interconnecting them, a distributing switch adapted to select and hold in readiness for use an idle link, a central office sending device transmitting impulses to said selected link, actuating means for said distributing switch, and a control circuit for said actuating means the closure of which is determined by said sending device.

38. In a telephone exchange system, a plurality of connective links having automatic switches for effecting connections, a primary distributing switch adapted to select and hold in readiness for use an idle link, a secondary switch adapted to select and hold in readiness for use a primary switch which has selected an idle link.

means for effecting connections by way of the selected idle links, a release for the primary switch, and a release for the secondary switch effective upon the release of the said primary switch.

39. In a telephone exchange system, a plurality of primary connective links having automatic switches, subscribers' lines to be interconnected thereby, a sending device intermediate calling and called subscribers' lines adapted to effect connection by way of said links between calling and called subscribers' lines, automatic switches through which said sending device is automatically associated with idle links when itself idle, secondary links adapted to automatically connect subscribers with the operator's set, a busy relay responsive to said connection to render the said operator's set and switches all busy to other connections, and a locking circuit for said relay controlled by the operator's sending machine, whereby the busy test is not removed until after the connection has been made.
40. In a telephone exchange system, a plurality of connective links having automatic switches, a distributing switch adapted to select and hold in readiness an idle link, a sending machine adapted to send selective impulses to said links through said distributing switch, a busy relay rendering said distributing switch and sending machine busy during the time impulses are being sent, and a locking circuit for said relay controlled by said sending machine whereby the machine and the distributing switch may be automatically released at the end of said period of impulses.
41. In a telephone exchange system, a plurality of subscribers' lines, a plurality of links for interconnecting the same, said links being provided with automatic switches for effecting said connections, operators' positions together with means to connect said positions with the links intermediate the calling and called subscribers' stations for the transmission of selective impulses in opposite directions to build up a connective circuit, an auxiliary communicating path by which the subscribers may communicate with an operator's position independently of the connective links, a call signal at said operator's position operated when the subscriber is connected with said position over said path, and a device rendering said operator's position busy to other calls upon the reception of said signal.
42. In a telephone exchange system, a plurality of subscribers' lines, a plurality of double headed connector links having automatic switches at each end through which connections may be made to calling and called lines respectively, an operator's transmitting device associated with said trunks,

and adapted to transmit the number of a calling subscriber to one end of said trunks, and the number of a called subscriber to the other end of said trunks, and secondary links between the subscribers' lines and the positions over which a subscriber may transmit a call for a connection between his own line and any other by way of said primary links.

43. In a telephone exchange system, a plurality of subscribers' lines, a plurality of connector links having automatic switches for interconnecting them, means at a central point intermediate the subscribers' lines for transmitting actuating impulses over said links to interconnect said lines in pairs, means at said point for registering incoming calls for transmission by impulses, and means auxiliary to said connector links wherever a calling subscriber may transmit calls for registration on said transmitting devices.

44. In a telephone exchange system, a plurality of subscribers' lines, a plurality of primary connector links having automatic switches for interconnecting them, a plurality of operators' positions having impulse transmitting devices adapted to be associated with said links to effect connections between the lines, a plurality of auxiliary secondary links containing automatic switches adapted to effect connections between subscribers and the operators' positions, operators' telephone sets, an operator's listening key adapted when pressed to connect and lock said listening set on one of said auxiliary paths, a starting key for the impulse transmitting device, and means controlled by said starting key for releasing said auxiliary path from the telephone set.

45. In a telephone exchange system, a plurality of subscribers' lines, a plurality of primary connector link circuits having automatic switches for interconnecting the same, a plurality of operators' key sets having impulse transmitting devices adapted to transmit impulses over said links when connected thereto and to effect connection between said lines in pairs, a plurality of secondary connector links comprising primary and secondary selector switches adapted respectively to select calling lines, and idle key sets, and means operative upon the transmission of impulses in response to any call to release said primary selector switches over said secondary paths from connection with any line, and said secondary selector switches from connection with the then busy operator's key set.

46. In a telephone exchange system, a plurality of subscribers' lines, a plurality of primary connector links containing automatic switches and adapted to effect connection between lines in pairs, a plurality of

operators' positions having impulse transmitting devices adapted to transmit selective impulses to the links when connected thereto and effect connections between the same, a plurality of separate secondary links containing primary and secondary selectors adapted respectively to effect connection with calling lines and idle operators' positions, said switches being connected permanently in series, a locking relay for the primary selector switch retaining the same in connection with the calling lines, means operable upon the transmission of selective impulses from the operator's position to release said primary selector switch, and means operable by said holding means upon its release for effecting the release of the secondary selector switches from the connected operator's position.

47. In a telephone exchange system, a plurality of subscribers' lines, a plurality of connective links for interconnecting them, a plurality of operators' sets associated with the connective links and adapted when connected therewith to transmit impulses thereto to effect connections between the lines in pairs, primary distributing switches containing non-multiple bank contacts of a plurality of connective trunks adapted to pick out and hold an idle link, and a secondary distributing switch containing multiplied terminal contacts of the primary distributing switches, one of the secondary distributing switches being associated with each operators' set, and adapted to pick out and hold a primary distributing switch connected to an idle link.

48. In a telephone exchange system, a plurality of subscribers' lines, a plurality of primary connector links having automatic switches adapted to effect connection between said lines in pairs, an operator's set adapted to transmit selective impulses over said links to effect said connections, a distributing switch associated with each key set and adapted to pick out and hold an idle link over which to transmit said selective impulses, a secondary selector switch and secondary connective circuit associated therewith over which a subscriber may communicate a call to an operator's set, and a busy relay operative upon communication of a call to make the operator's set and the link held by the distributing switch busy to other calls.

49. In a telephone exchange system, a plurality of lines to be interconnected, and a plurality of automatic connective links adapted to effect said interconnection, said links having primary selectors at one end, and secondary selectors at the other, the said primary selectors being normally active to select a calling line, and said secondary selector normally holding another line in

readiness for connection thereto through the primary selector.

50. In a telephone exchange system, a plurality of lines, a plurality of automatic connective links for interconnecting the same, each connective circuit having at one end a primary selector switch containing multiple terminals of the lines, and at the other end a secondary switch containing other multiple terminals of the lines, said switches having their movable terminals normally connected together, means whereby the primary switch is normally active to select a calling line of its group, and means whereby the secondary switch normally holds ready for connection with the selected line a pre-selected line of its group.

51. In a telephone exchange system, a plurality of lines to be interconnected, a plurality of automatic connective links for effecting said connection, each complete connective circuit having at one end a primary selector switch containing multiple terminals of the lines and at the other end a secondary switch containing other multiple terminals of the lines, said switches having their movable terminals normally connected together, means whereby said primary switch is normally active to select a calling line of its group, means whereby the secondary selector normally holds ready for connection with the selected line a pre-selected line of its group, and means whereby release of the primary switch effects operation of the secondary switch to preselect another line of its group for a succeeding connection.

52. In a system of communication between subscribers and operators, a plurality of automatic connective links adapted to connect calling subscribers' lines with positions of idle operators and comprising each a primary selector at one end adapted to connect with a calling subscriber's line and a secondary selector at the other end adapted to pre-select an idle operator's position, means controlled by the operator for releasing the primary selector switch, and means controlled upon the release of the primary selector switch for initiating actuation of the secondary switch to select another idle operator.

53. In a system of intercommunication between subscribers and operators, a plurality of automatic connective links containing each a primary selector adapted to connect with calling subscribers' lines and a secondary selector adapted to connect with idle operators' sets, means operative upon connection of a calling subscriber's line with an idle operator's set to render the said operator's set busy to secondary selectors disconnected from calling subscribers' lines, and means under control of the operator for

releasing the primary and secondary switches from the connection without destroying the established busy test.

54. In a system of intercommunication between subscribers and operators, a plurality of automatic connective circuits comprising each a permanently connected primary selector switch and secondary selector switch, said primary switch containing multiple terminals of the lines and said secondary switch containing multiple circuit terminals of operators' sets, means whereby the secondary switch is operative to hold in readiness an idle operator's key set, and means whereby the primary switch is operated to connect the same with the calling line.

55. In a telephone exchange system, a plurality of subscribers' lines to be interconnected, a plurality of primary double ended connective trunks having symmetrically arranged automatic selector switches at each end through which connection may be made simultaneously with two different lines, and a double operator's sending device associated therewith and adapted simultaneously to send actuating impulses to the opposite ends of said trunk whereby connection may be made between the two lines through said trunk.

56. A telephone exchange system including telephone lines; a plurality of link connectors each provided with operator controlled means at both ends to connect the same with lines; and operator's selector mechanism for selecting link connectors that are free for selection, said operator controlled means performing their line joining function independently of said selector mechanism, there being automatically operated switching mechanism for connecting the link connectors with called lines.

57. A telephone exchange system including telephone lines; a plurality of link connectors each provided with operator controlled means at both ends to connect the same with lines; and operator's selector mechanism for selecting link connectors that are free for selection, said operator controlled means performing their line joining function independently of said selector mechanism, there being automatically operated switching mechanism for connecting the link connectors with calling and 55 lines.

58. A telephone exchange system including telephone lines extending to an exchange having a plurality of operator's positions; link connectors common to the operators' positions and each provided with operator controlled means at both ends to connect the same with lines; and operators' link connector selectors for selecting link connectors that are free for selection, said operator

controlled means performing their line joining function independently of said link connector selectors, there being automatically operated switching mechanism for connecting the link connectors with calling lines.

59. A telephone exchange system including telephone lines extending to an exchange having a plurality of operators' positions; link connectors common to the operators' position and each provided with operator controlled means at both ends to connect the same with lines; and operators' link connector selectors for selecting link connectors that are free for selection, said operator controlled means performing their line joining function independently of said link connector selectors, there being automatically operated switching mechanism for connecting the link connectors with called lines.

60. A telephone exchange system including telephone lines extending to an exchange having a plurality of operators' positions; link connectors common to the operators' positions and each provided with operator controlled means at both ends to connect the same with lines; and operators' link connector selectors for selecting link connectors that are free for selection, said operator controlled means performing their line joining function independently of said link connector selectors, there being automatically operated switching mechanism for connecting the link connectors with calling and called lines.

61. A telephone exchange system comprising subscribers' lines, talking trunks, automatic switches for uniting said lines and talking trunks into conversational circuits, a control trunk, means whereby a calling subscriber may communicate his order to an operator over said control trunk, releasing means for said control trunk, additional means whereby an operator may directly control the operation of certain of said switches over a trunk separate from and after the release of said control trunk.

62. In a telephone exchange system including telephone lines, automatic switches for interconnecting said lines, an operator's position and order trunks extending thereto, means for automatically connecting with calling lines over said order trunks, service trunks extending to certain of said automatic switches, automatic means associated with said position for causing selection of certain of said automatic switches, additional automatic means associated with said operator's position for causing the automatic switches so selected to interconnect said lines corresponding to the communication received over said order trunks.

63. In a telephone exchange system including telephone lines, automatic switches

for interconnecting said lines, an operator's position, of means controlled upon the origination of a call to automatically extend the call over an order trunk extending to said position, service trunks extending from said position to said automatic switches over which certain of said switches are automatically selected, additional means associated with said position for causing the operation of the selected switches for causing the wanted line to be connected with the calling line extended to said position over said order trunk.

64. In a telephone exchange system, the combination with calling and called subscribers' lines, of automatic numerical switches for effecting connection between said lines, an operator's position, means as-

sociated with said position for causing a simultaneous action of said switches for effecting said connection.

65. In a telephone exchange system, the combination with a calling and a called subscriber's line, of automatic switches for extending the connection between said lines, an operator's position, of means associated with said position for causing the transmission of a predetermined number of impulses for simultaneously actuating said switches to extend the connection.

In testimony whereof I affix my signature in presence of two witnesses:

EDWARD E. CLEMENT.

Witnesses:
